SPARK PLUG

William E. Blood, New York, N. Y.

Application January 8, 1937, Serial No. 119,580

8 Claims. (Cl. 123—169)

This invention is a spark plug and is directed more particularly to the problem of eliminating excess heat in the ground electrode of the plug.

There is a tendency in many plugs to overheat in the ground electrode, especially in high compression engines, and this is generally caused by the fact that the heat absorbed by the electrode from the combustion charge is not properly conveyed away from the electrode through the shell 10 of the plug.

The present invention provides a simple and efficient means for accomplishing this result and is adapted to be employed in spark plugs of practically all kinds where this problem is involved.

Speaking generally, the invention consists in incorporating into the wall of the shell, a series of inlays extending longitudinally of the shell, in good heat conductive relation with the ground electrode and adapted to also have good heat conductive relation with the tapped hole in the cylinder block into which the plug is screwed. These inlays are of a metal of high heat conductivity and they are thus adapted to efficiently carry off the heat from the ground electrode and transfer it to the cylinder block where it is dissipated. The inlays may be made in any number and size to meet requirements of any particular plug and will effectually preclude the ground electrode from overheating and causing pre-ignition.

Features of the invention, other than those adverted to, will be apparent from the hereinafter detailed description and claims, when read in conjunction with the accompanying drawing.

35 The accompanying drawing illustrates different practical embodiments of the invention, but the constructions therein shown are to be understood as illustrative, only, and not as defining the limits of the invention.

40 Figure 1 is a side elevation of a plug embodying the present invention, the lower portion of the plug being shown in central section to more clearly disclose the structure thereof.

Figure 2 is a section through the shell of the 45 plug on the line 2—2 of Figure 1.

Figure 3 is a side elevation of the lower end portion of the plug shell shown in Figures 1 and 2.

50 Figure 4 is a view similar to Figure 2, but illustrating a modified form of construction.

The plug shown in Figure 1 is, in the main, substantially conventional, the chief departure from ordinary construction being in the shell portion 1 thereof. This shell may be of any 55 appropriate shape and the electrode 2 associ-

ated therewith may be also of any suitable kind, although it is shown in the form of a baffle plate, welded or otherwise secured to the lower end of the shell and provided with inwardly extending fingers 3 adapted to form, with the spindle head 4, 5 the spark gaps of the plug.

In incorporating the invention in a plug of this kind, I form, in the outer face of the threaded shank 5 of the shell, a series of longitudinal grooves, channels or recesses 6 of any appropriate 10 number and these recesses are made deeper in proximity with the ground electrode 2, as indicated at 7. In each of these grooves I place an inlay 8, which is preferably of copper, brass or some other metal of higher heat conductivity 15 than the metal of the shell 1 or the metal of the electrode 2. Copper may be conveniently used for this purpose, because it can be readily worked and it is a remarkably good heat conductor. The inlays are preferably made before the shank 5 is 20 threaded and the threading is carried out after the inlays have been completed, so that the threads are cut through the inlays and in the shank. Consequently when the plug is screwed 25 into the spark plug hole of a cylinder block, the threaded portions of the inlays make direct contact with the wall of the cylinder block and by virtue of the deepening of the recesses at 7, these inlays also have an appreciable contact area with 30 the ground electrode 2.

There is thus provided a direct path for the conduction of heat, through high heat conductive material, from the electrode 2 to the cylinder block and this will effectually protect the electrode 2 from overheating. The recesses or channels in 35 which the inlays are placed may be undercut or of any other appropriate cross section, so as to properly maintain the inlays in position.

In Figure 2 the channels are shown with substantially straight sides and the inlays may be 40 brazed, plated, or otherwise secured in these channels, although they may be simply forced into place under considerable pressure.

In Figure 4 the channels are shown as circular and are arranged substantially tangent to the 45 outer periphery of the shank 5 and may conveniently be formed by boring circular holes 9, as shown. Into these holes, metal of high heat conductivity is introduced in any suitable way, as by pouring or forcing it into place, to form the inlays.

The inlays need not necessarily have a homogeneous bond with the shell, although they may have if desired, and they need not have a homogeneous bond with the electrode, although they 55

preferably have, so as to insure a good heat transfer between the electrode and the inlays. This bond may be produced by soldering or brazing or otherwise.

5 In prior practice, it has generally been sought to conduct the heat from the ground electrode to the shell and then conduct it through the shell to the cylinder block. In accordance with the present invention, in contradistinction, it is not 10 the purpose of conducting the heat from the electrode to the shell, but rather to conduct the heat from the electrode, through the inlays, to the cylinder block, so that the shell is not depended upon as a heat carrier, but serves in a large 15 measure merely to serve as a support for the inlays which actually form the heat bridge between the electrode and the cylinder block. Therefore I am not particularly concerned with the relation 20 between the electrode and the shell other than that the shell must properly support the electrode, but I am primarily concerned with a proper heat path interposed substantially directly between the electrode and the cylinder block.

In carrying out the present invention in practice, it is desirable in every instance that the inlays should be so positioned that they are protected against the unrestricted action of the burning combustion charge upon them. In other words, they should not be open and exposed to the 25 burning charge for if this is permitted, they will tend to take up the heat directly from the charge rather than to draw heat from the ground electrode. Consequently they are positioned above the baffle and are so protected by the lower end 30 of the plug that the burning combustion charge 35 does not directly contact with them.

In both of the constructions which I have shown the inlays are at the outer surface of the shell, so that the threads are cut through said 40 inlays. I may, however, form the channels at the base of the threads, so that the threads do not cut through the inlays. The inlays should, however, be so close to the outer surface of the shell that the intervening material of the shell will 45 not appreciably retard the transfer of heat to the cylinder block. This should be borne in mind in the consideration of the appended claims, wherein I have referred to the inlays as in proximity to the outer surface of the shank to mean either at 50 or closely adjacent thereto.

The foregoing detailed description sets forth the invention in the preferred practical forms, but the invention is to be understood as fully commensurate with the appended claims.

55 Having thus fully described the invention, what I claim as new and desire to secure by Letters Patent is:

1. A spark plug comprising a shell having a threaded shank adapted to be screwed into the spark plug hole of a cylinder block, a ground electrode secured to the shank, and an inlay in the shank of the shell in good heat conductive relation with said electrode and extending away from the same in a direction longitudinally of the shank and in proximity to the outer surface thereof.

2. A spark plug comprising a shell having a

threaded shank adapted to be screwed into the spark plug hole of a cylinder block and provided in proximity to the outer surface of the shank with longitudinal inlays of metal of higher heat conductivity than the metal of the shell, and a 5 ground electrode secured to the lower end of the shank and in good heat conducting relation to the lower ends of the inlays.

3. A spark plug comprising a shell having a threaded shank adapted to be screwed into the 10 spark plug hole of a cylinder block and provided in proximity to the outer surface of the shank with longitudinal inlays of metal of higher heat conductivity than the metal of the shell, and a 15 ground electrode secured to the lower end of the 15 shank and homogeneously united to the inlays.

4. A spark plug comprising a shell having a threaded shank adapted to be screwed into the spark plug hole of a cylinder block and provided in its outer face with longitudinally extending 20 open sided channels, inlays positioned in said channels and of material of higher heat conductivity than the material of the shell, and an electrode secured to the shank and to the inlays and in good heat conducting relation to the 25 latter.

5. A spark plug comprising a shell having a threaded shank adapted to be screwed into the spark plug hole of a cylinder block and provided in its outer face with longitudinally extending 30 open sided channels, inlays positioned in said channels and of material of higher heat conductivity than the material of the shell, and an electrode secured to the shank and to the inlays and having a fused bond with the latter.

35 6. A spark plug comprising a shell having a threaded shank adapted to be screwed into the spark plug hole of a cylinder block and provided with a plurality of longitudinal passages extending into the body of the wall of said shank from 40 the free end thereof for more than one-half the height of the shank, inlays in said passages and of metal of better conductivity than the metal of the shell, and an electrode secured to the shell and also secured to the several inlays.

45 7. A spark plug comprising a shell having a threaded shank adapted to be screwed into the spark plug hole of a cylinder block and provided with at least one longitudinal passage extending into the body of the wall of said shank from the 50 free end thereof for more than one-half the height of the shank, an inlay in said passage and of metal of better conductivity than the metal of the shell, and an electrode secured to the shell and having good heat conductive relation with 55 the inlay.

8. A spark plug comprising a shell having a threaded shank adapted to be screwed into the spark plug hole of a cylinder block, inlays in proximity to the outer surface of the shank and extending longitudinally thereof and of metal of higher heat conductivity than the metal of the shell, and a baffle electrode secured to the lower end of the shank and to the inlays, said inlays being protected from direct contact with the 60 combustion charge.

WILLIAM E. BLOOD.
